UNITED STATES PATENT OFFICE.

JOHN T. DAVEY, OF ASHLAND, WISCONSIN.

MOISTENING-CASE FOR CIGARS.

SPECIFICATION forming part of Letters Patent No. 663,329, dated December 4, 1900.

Application filed June 2, 1900. Serial No. 18,850. (No model.)

To all whom it may concern:

Be it known that I, JOHN T. DAVEY, a citizen of the United States, residing at Ashland, in the county of Ashland and State of Wisconsin, have invented new and useful Improvements in Moistening-Cases for Cigars, of which the following is a specification.

The object of my invention is to provide an improved moistening-case for cigars and to the like; and the same consists of a case or receptacle for a cigar-box having an imperforate pivoted cover, a turn-button on said cover adapted to engage the lid of a cigar-box contained within said case for maintaining said lid in a partially-open position when said cover is closed and for moving said lid to its open position when said cover is opened, and moistening means in the bottom of said case outside the cigar-box therein.

20 The invention also consists in certain features and details of construction and combinations of parts, which will be hereinafter more fully described and claimed.

In the drawings forming part of this specification, Figure 1 is a transverse vertical section of my improved moistening-case, showing a cigar-box contained therein. Fig. 2 is a sectional plan taken on the line 2 of Fig. 1. Fig. 3 is a rear elevation of a portion of 30 the case. Fig. 4 is a perspective view of the same, showing the lid raised.

Like reference-numerals indicate like parts in the different views.

My improved moistening-case 1 is preferably constructed of sheet metal, although, of course, it may be made of any other material suitable for the purpose. It is provided with an imperforate hinged top or cover 2, having flanges 3 around the edges thereof, which are 35 adapted when the cover is in its closed position to embrace the upper ends of the sides of the case. The said cover is normally maintained in its closed position by a spring 4, which may be of any suitable form and construction, but, as shown, consists of a coil-spring mounted upon a rod or bar 5, secured in lugs or ears 6 on the rear side of the case 1, and a bail 7, pivoted to said rod or bar engaging the upright portion or back 8 of the 45 cover 2 and itself engaged by the ends of said coil-spring.

Within the case 1 is located a false bottom

9, having downwardly-depending side and end flanges thereon which serve as supports for said false bottom and provided with a 55 series of perforations 10. Beneath the false bottom 9 is a mass of sponge 11 or other absorbent material the moisture from which may pass up through the perforations 10. The cigar-box 12, which my improved case is 60 adapted to hold, is of slightly-smaller dimensions than said case and when in place therein rests upon the upper surface of the false bottom 9. In order to retain the same in place and to hold it on all sides at a short distance 65 from the inner surface of the sides of said case, I secure to the sides of the case inwardly-extending leaf-springs 13, as clearly shown. When the box 12, therefore, is in place within the case 1, an annular space is provided around 70 the outside thereof.

Pivoted to the inner surface of the cover 2 is a turn-button or catch 14, between which and said cover the lid 15 of the cigar-box 12 is adapted to be inserted and held. The 75 parts just described are so arranged that when the cover 2 is in its closed position the case 1 will be practically though not absolutely airtight. The lid 15 of the cigar-box, however, will be held slightly raised by the turn-button 14 in order to permit of the entrance of moisture to the contents of the box 12.

The upright portion or back 8 of the cover 2 serves as a handle or engaging portion by means of which the cover 2 may be raised. 85 It also may serve as a surface upon which advertisements or labels may be applied. On the other hand, it may be dispensed with altogether and will be when the case is to be used elsewhere than in a store.

It may be desired at certain times to hold the cover 2 and the box-lid 15 in their open positions. To provide for this, I pivot to one end of the cover 2, preferably upon one of the end flanges 3, a stop-link 16, which is 95 adapted to engage a projecting portion 17 on the body of the case. Instead of providing the spring 4 for closing the cover 2 automatically I may dispense with this spring altogether and provide for the closing of the cover 100 2 by gravity. In using my improved moistening-case the false bottom 9 is removed and the mass 11 of sponge is soaked with water. The false bottom 9 is then reapplied and the

box 12 inserted into the case upon said false bottom. In inserting the same the springs 13 are compressed, so that the said box is retained in place by the action of said springs 5 on the sides and ends thereof. The turn-button 14 having been turned to a point in line with the direction of the length of the cover 2, the lid 15 of the box 12 is secured to the cover 2 by turning the button or catch 14 10 to a position at right angles to the direction of the length of the cover 2, at which time said button or catch engages the inner surface of said lid 15. The cover 2 being now allowed to return to its closed position, the 15 case containing the box may be placed away within an ordinary cigar-case upon a shelf or on any suitable support. Meanwhile the moisture from the mass 11 of absorbent material passes up through the perforations 10 in 20 the false bottom 9 and thence around the annular space between the box 12 and the sides of the case 1 and into said box through the opening between the lid 15 and the top of said box. It is of course understood from 25 what has heretofore been stated that the lid 15 is normally maintained in a partially-open position. When it is desired to remove a cigar from the box 12, either for use or sale, the hand is applied to the upright portion 8 30 of the cover 2 and the said cover elevated thereby. The opening of the cover, however, also opens the lid 15 of the box 12 and exposes the contents of said box. As soon as 35 the desired number of cigars have been removed the pressure is relieved from the upright portion 8 and said cover 2 returns to its closed position automatically, either through the action of the spring 4 or by gravity, according to whether or not said spring 4 is 40 employed.

I have heretofore stated that the cover 2 of my improved case is imperforate and is provided with a turn-button 14 thereon, which

is adapted to engage the lid of the cigar-box contained in said case. By making the cover 45 2 imperforate all escape of vapors from the inside of the case is prevented when the cover 2 is closed, but the same are permitted to enter the cigar-box through the space between the upper edge of said box and the lid thereof. 50

Having now described my invention, what I claim as new, and desire to secure by Letters Patent, is—

1. A moistening-case for cigars and the like, having an imperforate hinged cover, moistening means in the bottom of said case outside the cigar-box contained therein, and a pivoted turn-button on said cover for retaining the lid of the cigar-box contained within said case in a partially-open position when said cover is closed and for moving said lid with said cover when the latter is opened, as and for the purpose set forth. 55

2. In a moistening-case for cigars and the like, the combination with a perforated false bottom having supporting side flanges thereon, and having a mass of absorbent material beneath the same, and a spring-actuated imperforate cover for said case, of springs secured to the inner surfaces of the sides of 70 said case adapted to engage and retain in place a cigar-box of smaller dimensions than said case and to provide a space around said box, and a pivotally-mounted catch on the inner surface of said cover adapted to engage 75 the lid of said cigar-box for holding said lid in a partially-open position when said cover is closed and for moving said lid with it when said cover is opened.

In testimony whereof I have hereunto set 80 my hand in presence of two subscribing witnesses.

JOHN T. DAVEY.
